OSCAR R. WIKANDER, OF PITTSBURGH, PENNSYLVANIA, ASSIGNOR TO EDGEWATER STEEL COMPANY, OF PITTSBURGH, PENNSYLVANIA

CUSHIONING-SPRING CONSTRUCTION

Application filed August 30, 1926. Serial No. 132,407.

This invention relates to cushioning spring constructions, and particularly to bolster springs for railway car trucks, and for other similar uses, in furnishing an elastic support for a load to be carried and to absorb shocks and jars, etc.

The main object of the bolster springs of a railway car truck is, of course, to furnish an elastic support for the load carried by the truck and to absorb the vertical shocks transmitted to the truck from the track. In addition, however, to this action of absorbing the vertical shocks, it is desirable to construct or arrange these springs so as to adapt them to also take up any shocks in a horizontal direction, which may be imparted from the track to the truck or caused by relative horizontal displacements of the bolster with respect to the spring plank.

In structures of the character heretofore in use, the elastic action of the springs themselves in resisting horizontal displacement of the bolster in regard to the truck frame, has been partly or entirely depended upon to absorb the horizontal shocks, such action necessarily requiring distortion of the springs laterally in one direction or the other from their normal vertical plane. Such distortion or elastic action in horizontal directions involves, however, additional local stresses in the spring, which, as a rule, are heavily stressed by the vertical load alone, and, in some cases as, for instance, in the use of ring springs, is detrimental in causing interference with the main function of the spring, to wit, that of absorbing vertical shocks.

The object of the present invention is to provide a cushioning spring construction for securing the desired elastic resistance against lateral or longitudinal shocks without subjecting the springs to any lateral force and while limiting the action on the same to straight line compression loads.

My invention, therefore, consists in the provision of means adapting the spring to perform its main function of cushioning vertical shocks, while permitting it to cushion horizontal shocks without lateral bending or distortion.

In the accompanying drawing illustrating the invention,—

Figure 1 is a vertical section showing the application of the invention in conjunction with the bolster and truck frame of a car, and illustrating in dotted lines a horizontal shock absorbing action.

Figure 2 is a top plan view of the cushioning device shown in Figure 1.

Figure 3 is a sectional side elevation of a bolster and truck frame and a modified form of shock absorbing device.

Figure 4 is a plan view of the shock absorbing device shown in Figure 3.

Figure 5 is a view similar to Figures 1 and 3 of another modified form of shock absorbing device.

Figure 6 is a top plan view of the shock absorber shown in Figure 5.

Referring now more particularly to the structure shown in Figures 1 and 2, 1 designates generally the shock absorbing device, 2 the bolster, and 3 the spring plank supported by the truck frame 4.

The shock absorbing device 1 comprises a cushioning spring 5, of ring spring type, although a spring of any other suitable type may be employed, said spring being arranged within an enclosing casing comprising two cup-shaped telescopic engaging members 6 and 7. The spring is mainly enclosed in the bottom section 6 of the casing, with its upper end projecting therefrom and enclosed within and elastically supporting the upper casing section 7, the said two casing sections 6 and 7 being freely movable in the contracting and expanding movements of the spring. These casing sections not only house and protect the spring from the access of dirt, dust and other foreign substances but support the spring for contracting and expanding movements in an axial direction only, the spring being thereby sustained from horizontal or lateral distortion or bending movements under relative horizontal, lateral and longitudinal movements between the truck frame and bolster.

The casing may be of any suitable cross-sectional form, but, in the present instance, is shown as of rectangular or oblong rectan-

gular form and engaged with the bolster 2 and spring plank 3 so as to be held against displacement, while at the same time permitting it to tilt longitudinally or laterally of the truck bolster when, through relative movements between the bolster and spring plank, the bolster moves either longitudinally or laterally out of proper position. To this end the opposed faces of the bolster and 10 spring plank are provided with seat recesses 8 and 9 in which the top portion of the casting section 7 and bottom portion of the casting section 6 are respectively received and held. With this construction, it will be seen 15 that the spring will move normally in a straight vertical direction in absorbing vertical shocks and jars. In the event, however, of a relative displacement between the bolster and spring plank, either longitudinally 20 or laterally of the truck, such as the longitudinal displacement of the bolster illustrated in dotted lines in Figure 1, the shock absorbing device as a whole will tilt in the direction of the displacement. When so arranged 25 the spring, while maintaining a straight line or axial cushioning motion, will absorb the vertical shocks and jars as well as the horizontal shocks or jars incident to the displacement, the horizontal shocks being 30 sustained without causing lateral bending or distortion of the spring or interference with its vertical shock absorbing motion.

In Figures 3 and 4 I have shown a modified form of my invention in which the sections 6^a and 7^a of the spring casing or housing are provided respectively with base and head portions 10 and 11 of uniform diameter, and each of greater diameter than its casing section, said base and head sections being provided 35 with convex outer faces fitting in the seat recesses 12 and 13 and adapting the cushioning device to have an easy and wide amplitude of tilting motion.

In Figures 5 and 6 I have shown another modified form of construction of the casing in which the casing sections 6^b and 7^b are provided with diametrically extending oblong rectangular enlargements 10^a and 11^a forming comparatively wide rocker bars or ribs 40 which engage the seat recesses and on which the shock absorbing device is adapted to tilt. These rocker bars or ribs have convex outer faces, which may extend longitudinally thereof only, or both longitudinally and 45 transversely thereof, to adapt the shock absorbing device to tilt with greater freedom in one direction or the other or with equal degrees of freedom in both directions.

The foregoing are illustrations of some of 50 the many shapes or forms which the seat portions of the casing sections may take, it being obvious that the said seat portions may vary in form within wide limits, as desired, or as 55 found best suited under different conditions of use. It will also be understood that my

invention is not limited in use to its purpose as a shock absorber for railway trucks, as it may be employed in various other types of devices or apparatus for the purpose of forming an elastic support for a load, and to take 70 up shocks and jars falling in a single direction or in a plurality of directions. In the action example illustrated in dotted lines in Figure 1, in which the bolster is shown as displaced horizontally with relation to the 75 spring plank and the shock absorbing device correspondingly tilted, it will be obvious, assuming that the load on the spring has remained practically constant, that the displacing motion of the bolster involves a lifting 80 of the load against the force of gravity, which latter force will tend to bring it back to the normal full line position shown in Figure 1, in which motion the cushioning device is also returned to normal position.

While a cushioning spring of ring type is shown in the present disclosure, it is apparent that a coiled spring or leaf spring may be used in its place, and that while a straight line motion maintaining means is disclosed in the 90 form of a casing composed of telescopic cup-like sections, other means for sustaining and maintaining the straight line motion of the spring may be employed, without departing from the spirit of the invention.

Having thus fully described my invention, I claim:

1. The combination with two spaced and relatively movable load carrying members, of a cushioning unit comprising a ring spring disposed between said members, and an enclosing casing for the spring holding the spring elements assembled and comprising telescopic sections operative to positively guide the spring so as to maintain a straight line motion thereof, said casing having connection at its opposite ends with the load carrying member for universal tilting motion with the spring while maintaining a straight line motion of the spring in the cushioning movements of the same and the telescopic sections of the casing.

2. The combination with two spaced and relatively movable load carrying members provided with seat recesses in their opposed faces, of a cushioning spring disposed between said members, and an enclosing casing for the spring comprising sections telescopically connected to secure a straight line cushioning motion of the spring, said casing loosely engaging said seat recesses so as to permit unitary tilting motion of the casing and spring while maintaining such straight line motion.

3. The combination with two superimposed spaced and relatively movable load carrying members, of a shock absorber comprising a cushioning spring disposed between said members, and abutments for the ends of the spring enclosing the spring, said abutments

having an intersliding engagement with each other for positively obtaining straight line compressive and expansive motions of the spring along the longitudinal axis of the absorber and said abutments having engagement with the load carrying members such as to permit universal tilting motions of the spring and its abutments without impairing the straight line motion of the spring or dis-
10 turbing its symmetrical position around its longitudinal axis.

In testimony whereof I affix my signature.
OSCAR R. WIKANDER.
